A. R. MUNYARD

DOLL

Filed March 23, 1923

2 Sheets-Sheet 2

UNITED STATES PATENT OFFICE.

ALAN ROSS MUNYARD, OF CATFORD, ENGLAND.

DOLL.

Application filed March 23, 1923, Serial No. 627,147, and in Great Britain January 25, 1923.

This invention relates to dolls of the type in which the facial expression can be changed. The invention may also be applied to toy animals to which different facial expressions can be imparted.

The object of the invention is to provide a doll which will, so nearly as possible, simulate the actions and changeable moods of a child thereby creating greater and more prolonged amusement than playing with dolls has heretofore afforded.

The invention consists, mainly, in the provision of a doll or the like of which the facial expression changes gradually as, for instance, from sadness to cheerfulness.

Further, the invention consists in the provision of a doll or the like of which the facial expression will change gradually when picked up from a reclining or sitting position and rocked as in the act of caressing.

Further, the invention consists in the provision of a doll of which the pleasant facial expression produced by rocking will be maintained so long as the doll is not placed in a recumbent position.

Further, the invention consists in the provision of a doll which, when in a recumbent position on one of its sides, will maintain a pleasant expression, but which, when placed upon its other side will immediately resume a fretful expression.

Further, the invention consists in the provision of a doll which, so long as it is held out of a recumbent or sitting position and slightly rocked will open and close its eyelids as in the act of winking.

Further, the invention consists in the provision of a doll having mechanism and alternative parts of mechanism, substantially as and producing the effects hereinbefore described, the mechanism being preferably arranged in such manner that it can be integrally placed within the doll and removed therefrom for repair.

Reference being had to the accompanying drawings:

Fig. 1 shows the head of a doll, partly in section, and illustrating the mechanism therein, also in section.

Fig. 2 is a plan of the mechanism, the operating cords being omitted to ensure clearness.

Fig. 3 is a section through the base or support for the mechanism, the section being taken in a direction which is at right angles to that shown in Figure 1.

Figs. 4 and 5 show, respectively, fragmentary end and side views of the supporting rods and guides for the operating cords and the arrangement of springs employed.

Figs. 6 and 7 show, respectively, plan and front view of the means for operating the eye-brows.

Fig. 8 is a fragmentary view, in section illustrating the means for operating a dimple.

Figs. 9 and 10 illustrate the method of mounting pendulums which constitute parts of the mechanism.

Figs. 11 and 12 illustrate means and alternative means, respectively, for releasing certain mechanism to restore the face to its normal expression after being gradually changed to an abnormal expression.

Fig. 13 is a fragmentary sectional view illustrating an alternative method of operating the eyes.

Fig. 14 is a view illustrating an alternative method of operating the lips, the method being also applicable to the operation of the eyebrows.

Figure 15 is an enlarged view showing the connections for actuating the eyebrows.

Fig. 16 is a diagrammatic view showing the connections between the pendulum, the rack bar and the pendulum-actuating cord.

The mechanism,—with the exception of the movable parts of the face such, for instance, as the eyes, eye-lashes, tears, eyebrows, lip or lips, and dimple—are supported by a base 1. This base consists of a stamped diaphragm having, preferably, a stiffening annular bead 2, a central opening 3 and two depending flanges 4, 5 formed integrally with the base, the flange 4 having a perforated lug 6, and a channel-shaped recess 7. This base rests upon a seat 8 and may be retained in place in any suitable way as, for instance, by means of a severed spring-ring 9 having its periphery sprung into an annular recess 10.

The mechanism, carried by the base, for operating the movable parts of the face, comprises a pendulum 11 of which the rod 12 is

flattened and perforated as at 13, or twisted into a loop to enable it to be passed over and mounted upon a wire support 14 which is horizontally disposed and retained between 5 the flanges 4 and 5, by having its ends bent at right-angles as shown at 15.

A rack-bar 16 fits and is capable of reciprocating within the recess 7 and has teeth 17 which are engaged by the upper part of the 10 pendulum rod 12. The rack-bar has a slot 18, an eye or staple 19, and is retained within the slot 7 by plates 20 which are soldered or otherwise secured to the base.

A pawl 21, having a projection 22, engages 15 the teeth 17 of the rack, is retained within a housing 23 which is soldered or otherwise secured to the base, and is normally pressed outwardly from its housing by a spring 24, there being a slot 25 in the housing to permit of the rearward movement therein of the projection 22.

A horizontally disposed wire support 26, held in the flanges 4 and 5, as described with reference to the wire 15, carries a pendulum 27, of which the rod 28 has a loop 29, above which is its extremity 30. The stem 28, and also the stem 12 of the pendulum 11 are held in place upon the respective supports 26 and 14 by washers 31, 32 which are secured in place by solder 33 or in any other suitable way. The washers 32 have rounded inner surfaces to permit the rod 12 to rock in a direction which is parallel to the supporting rod 14 as well as at right angles thereto, the 35 perforation in the pendulum rod being large enough to permit of such combined movements.

Brackets 34, preferably consisting of 40 lengths of wire bent into suitable shape and soldered to the flanges 4 and 5, respectively, are each formed with a loop 35 to encompass the rods 28 and 12 to limit the amplitude of the pendulums. These loops may be covered with rubber to eliminate noise occasioned by 45 contact of the rods with the brackets when the pendulums swing.

A pawl or lever 36 upon a wire support 37 which is secured in and between the flanges 4 and 5, as described with reference to the 50 supports 14 and 26, projects through the slot 18 of the rack-bar 16 and is bent and shaped in such manner as to extend over the pendulum rod 28, the pawl having an indentation 38 to engage the extremity 30 of the rod. The pawl is normally retained in a 55 forward position by a spring 39 retained in perforations in the lug 6 and pawl 36 respectively, there being a stop-pin 40 projecting between the flanges 4 and 5 to limit 60 the forward movement of the pawl.

The face is made of rubber or similar elastic substance or, as shown in Figure 1, of 65 rubber 41 covering a base of harder substance 42, there being openings 43, 44, 45, 46 in the latter either to receive movable parts

and to permit them to be moved in the openings or the rubber to be stretched and consequently moved at those places as herein-after explained.

The eye-lids 47, 48 have inner and outer 70 curvilinear surfaces to conform to the similar surfaces of the openings 44 and the eye-balls 49 respectively, eye-lids having eyelets 50 at their inner portions. Each eye-ball has a wire stem 51 which extends through a slot 75 52 in each upper eye-lid.

Wire stems 53 extend through the substance 80 44 and carry tear drops 54 of glass or the like which can be withdrawn into recesses 55—see Figure 13.

The eye-brows 56 are attached to the rubber covering 41 and the lips 57 are formed thereof.

Rubber pads 58, 59, 60 are cemented to the covering 41 and enclose metallic washers 61 85 (Fig. 8) to which operating cords are attached.

Upon the base 1 are a pair of standards 90 having flanges 63 by which they are soldered or otherwise secured to the base. The standards retain transversely arranged cord guides 63^a, 63^b, 63^c, 63^d to which are soldered angle-pieces 64, each having a slot 65 to guide the cord. These angle pieces constitute abutments for springs 66 which encompass the cords and are retained in place thereon or to wire stems 67, 68 and the stems 51 and the stems 53 by washers 69, the stem 68 being attached to the stems 51 and the stem 67 to the eyelet 50 of the lower eye-lid. 95

The movable parts of the face described are operated by cords 70, 71, 72, 73, 74, 75, 100 76. The cords 70 to 74 inclusive, are all attached to the eyelet 19 on the rackbar and the cords 75 and 76 to the eye 29 of the pendulum rod 28. The cord 70 passes over a bridge 77, projecting upwardly from the base 1, and is attached to the rubber pad 59 connecting with the lower lip 57. The cord 71 passes under the bridge and is attached to 110 the parts 61, 60 in the recess 46. The cord 72 passes under the bridge and is attached to the stem 68, after passing under the guide rod 63^d and through a spring 66. The cord 73 passes over the uppermost guide-rod 63^a 115 and is attached to the rubber pad 58 connecting with eye-brows 56. The cord 74, passes over a guide-rod 63^b and is attached to the stems 53 of the tears. The cord 75 is attached to the loop 29 of the pendulum 120 rod 28, passes under a guide-rod 63^c through a spring 66 and is attached to the stem connecting with the upper eye-lid. The cord 76, attached to the loop 29, passes over the guide-rod 63^b, through a spring 66, and is 125 attached to the stem 67 connected to the lower eye-lid.

It is to be understood that those of the cords which are connected to the eyes, eye-lids, and eye-brows are duplicated. If 130

found necessary, the cords 70, 71, 72, 73 and 74 comprise springs 78 for a purpose hereinafter described.

The upper extremity of the pendulum rod 12 has attached to it a cord 79 which passes through an eyelet 80 in a guide-frame 81 secured to the base. The cord passes through a perforation 82 and is attached to an arm 83 (Fig. 11) projecting from the pivot of one of the legs 84. Alternatively, the cord 79 may be attached to one end 85 of a lever 86, pivoted at 87 to an upright 88 and attached to a push-button 89 by means of a wire stem 90, the button being situated within a housing 91 secured to the lower body portion of the doll. A spring 95 keeps the push-button normally pressed outwards.

The cord 79 is attached to a simple eye at the top of the pendulum rod 12, as shown in Figure 2, so that when pulled upon it merely draws the pendulum rod over to one side clear of the teeth 17, and, further, there is no spring for drawing the rack bar back to its normal position when thus released, but this movement is effected by the numerous springs 66 and 78 in the cords which become slightly stretched when the movable parts of the face have reached the extent of their movement.

In Figure 13 the eyes are shown as turned inwards. The movement of the eyes is, in such instance, effected by wires 92, springs 66 and cords 95. This movement of the eyes can be either alternative to the downward movement shown in Figure 1, or additional thereto as will be readily understood.

In Figure 14 is indicated an alternative method of and means for operating the lips. The under lip 57 has embedded in it a leaf spring 93, pivoted at two points 94 to the solid portion of the face, so that when the extremities 94 of the spring are raised by the cords, the lips will part. The same device may be adapted to effect movement of the eye-brows.

The operation of the mechanism is as follows:—

Normally, the parts of the mechanism are in the position shown in the drawings and the face has a fretful expression. Slightly rocking the doll forwardly and rearwardly will cause the pendulum 11 to engage the teeth of the rack-bar successively, the upper part of the rod 12 riding over the teeth, when moving in one direction, by reason of its ability to swing in two directions as hereinbefore described. Because of the space between the pendulum rod and the projection 22 of the pawl the latter will not be operated. The travel of the rack-bar will gradually raise the eye-brows, raise the eyes, withdraw the tear, part the lips and cause a dimple to appear in the cheek. When the rack-bar reaches the end of its travel, the end of the slot 18 therein will

have pushed back the lever 36 and released the pendulum 27 which, commencing to rock, will open and close the eye-lids as in the act of winking. This performance will continue until the doll is laid to rest upon its right side when, the pendulum 11, moving in a downward direction, will cause the upper part of the stem to move clear of the rack teeth and, subsequently coming into contact with the projection 22 on the pawl 21, will push the latter inwards. This action will release the rack which will then resume its normal position under the influence of the springs 66 and the face will resume its normal fretful expression. The return movement of the rack will release the lever 36 which will be drawn forwardly by its spring 39 and reengage the extremity 30 of the pendulum stem 28. It will be understood, however, that when the doll is laid to rest upon its left side after the rack has been caused to operate the movable parts of the face, the upper part of the pendulum rod 12 will remain in contact with the teeth of the rack-bar and the doll will recline with a continued pleasant expression. Either additionally or alternatively to the method described, the rack can be released by causing the doll to assume a sitting posture, in which event, the leg 84 will move upwardly and the arm 83, pulling upon the cord 79 will pull the upper part of the pendulum rod 12 against the pawl, thus disengaging it from the rack-teeth. The same effect can be produced by the mechanism shown in Figure 12, it being understood that the weight of the doll will cause the push-button 29 to recede into its housing and a pull to be exerted upon the cord 79.

As hereinbefore described, the cords 70, 71, 72, 73 and 74—and, if necessary the other cords also—comprise springs 78, so that in the event of the movable parts of the face to which the cords are attached arriving at the limit of their permitted movement before the rack-bar has reached the limit of its travel, the springs will elongate and not prevent the completion of the movement of the rack-bar.

It is to be noted also, that those of the cords which are attached to movable parts of the face which have small movements as, for instance, the eye-brows and tears are attached directly to the eyelet 19 of the rack-bar for the reason that the downward pull on the cords will not be so direct and extensive as it would be if the cords passed beneath the bridge 77.

What I claim is:—

1. A doll having changeable features, a reciprocating rack bar and cooperating mechanism connecting the same with the movable features including movable eyes, eyebrows and lips, whereby the facial expression can be caused to change gradually,

means for reciprocating said rack bar, and connections for automatically maintaining the facial expression when the doll reclines upon one of its sides.

5 2. A doll having changeable features, a reciprocating rack bar and cooperating mechanism connecting the same with the movable features including movable eyes, eyebrows and lips, whereby the facial expression can be caused to change gradually, means for reciprocating said rack bar, connections for automatically maintaining the facial expression when the doll reclines upon one of its sides, and a single base upon which 10 the operating parts are all mounted.

15 3. A doll having changeable features and a reciprocating rack bar and cooperating mechanism connecting said rack bar with the movable features of the face whereby the facial expression can be caused to change gradually and means for automatically maintaining the changed expression when the doll reclines upon one of its sides but of 20 which the normal facial expression will be assumed when the doll reclines upon its other side by means of mechanism situated upon a single base capable of insertion and removal from the interior of the doll and comprising said rack bar operating in conjunction with a pendulum and a means for 25 operating the rack bar, and separate and independent means to release the rack bar to normal position.

30 4. A doll having movable features and mechanism within the doll whereby the facial expression of the doll can be caused to change gradually and means for automatically maintaining the changed expression when the doll reclines upon one of its sides, but of which the normal facial expression will be assumed when the doll reclines upon its other side, said mechanism comprising a rack bar, and connections between said rack bar and the movable facial features operating 35 in conjunction with a pendulum, and capable of being released after gradual movement in one direction by certain movements of the pendulum thus permitting said rack to move in a reversed direction.

40 5. A doll having movable facial features including movable eyes, eyebrows and lips, a reciprocating rack bar, means for actuating the rack bar and connections between the same and the movable facial features to cause the facial expression to gradually change, and means for automatically maintaining the changed expression, independent means for returning the rack bar to normal position and means whereby when the changed expression has been attained said 45 second named means will be released and the eyes, eyebrows and lips moved and parts of the mechanism released and certain parts appertaining to the facial features will be

operated independently of other movable parts of the face.

6. A doll having movable features and mechanism within the doll whereby the facial expression of the doll can be caused to change gradually and of which the changed expression can be maintained or released, but in which, when said changed expression has been attained, the eyes, eyebrows and lips may be moved and certain parts of mechanism may be released, said mechanism comprising a lever adapted to engage a pendulum rod, a spring to retain the lever normally in engagement with the pendulum rod, a stop to limit the movement of the lever when in engagement with the pendulum rod and means for operating the lever to release said pendulum rod to operate certain movable parts appertaining to the face independently of the eyes, eyebrows and lips, said means being connected with the latter 55 named features of the doll to move the same.

7. A doll having movable features and mechanism within the doll whereby the facial expression of the doll can be caused to change gradually and of which the changed expression can be maintained or permitted to resume its normal state, said mechanism comprising a base, a toothed rack capable of reciprocation, a pendulum adapted to move the toothed rack, brackets for limiting the amplitude of the pendulum, a pawl for retaining the toothed rack in abnormal positions, said pawl having a projection adapted to be operated by the pendulum rod to release the toothed rack, flexible connections attached at one end to the toothed rack and at the other end to the movable features, guides for said connections, standards upon the base to support the guides, and springs adapted and arranged to operate in conjunction with said flexible connections and guides.

8. A doll having movable features and mechanism within the doll whereby the facial expression of the doll can be caused to change gradually and of which the changed expression can be maintained or permitted to assume its normal state, said mechanism consisting of a base, a toothed rack capable of reciprocation, a pendulum adapted to move the toothed rack, a bracket for limiting the amplitude of the pendulum, a pawl for retaining the toothed rack in abnormal positions, said pawl having a projection adapted to be operated by the pendulum rod to release the toothed rack, a lever pivoted to the base and adapted to engage the rod of a second pendulum, a bracket for limiting the amplitude of said second pendulum, a spring to retain said lever normally in engagement with the rod of said second pendulum, a stop to limit the movement of the lever, said lever adapted to be operated by the toothed rack 115 120 125

when it approaches the limit of its movement in one direction to release said second pendulum rod to operate certain movable features of the face of the doll independently of other movable features thereof operated by the rack, flexible connections joining the second pendulum rod and the rack with the respective features operated by

each, guides for said connections, standards upon the base to support the guides, and springs adapted and arranged to operate in conjunction with said flexible connections and guides.

In testimony whereof I have signed my name to this specification.

ALAN ROSS MUNYARD.
